US00D885187S

(12) **United States Design Patent** (10) **Patent No.:** **US D885,187 S**
(45) **Date of Patent:** **** May 26, 2020**

(54) **COMPARTMENTED CARTON INSERT**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/673,294**

(22) Filed: **Dec. 13, 2018**

Related U.S. Application Data

(62) Division of application No. 29/582,402, filed on Oct. 27, 2016, now Pat. No. Des. 840,232.
